DESIGN FOR A BACKGAMMON GAME BOARD

Oswald B. Lord, New York, N. Y.

Application July 29, 1935, Serial No. 57,857

Term of patent 14 years

To all whom it may concern:

Be it known that I, Oswald B. Lord, a citizen of the United States and a resident of the city of New York, county of New York, and State of New York, have invented a new, original, and ornamental Design for a Backgammon Game Board, of which the following is a specification, reference being had to the accompanying drawing, forming part thereof.

The figure is a plan view of a backgammon game board, showing my new design.

The design has no material or appreciable third dimensional thickness.

The design consists of a plurality of backgammon tables arranged radially in pairs with respect to each other on a playing surface, and each of said tables consisting of six pointed elements, and each of said elements being subdivided into two equal parts contrasting with each other in color.

I claim:

The ornamental design for a backgammon game board, substantially as shown and described.

OSWALD B. LORD.
